W. L. DAVIS.
CINCH BUCKLE.
APPLICATION FILED OCT. 8, 1918.

1,368,903.

Patented Feb. 15, 1921.

UNITED STATES PATENT OFFICE.

WILLIAM LOREN DAVIS, OF CHICAGO, ILLINOIS.

CINCH-BUCKLE.

1,368,903.

Specification of Letters Patent. Patented Feb. 15, 1921.

Application filed October 8, 1918. Serial No. 257,331.

To all whom it may concern:

Be it known that I, WILLIAM LOREN DAVIS, a citizen of the United States, residing at Chicago, in the county of Cook and 5 State of Illinois, have invented new and useful Improvements in Cinch-Buckles, of which the following is a specification.

This invention has reference generally to improvements in that class of inventions 10 known as buckles, buttons and clasps, and more particularly relates to a cinch buckle.

It is the principal aim and object of the present invention to provide a device of the above mentioned character designed to 15 be used for fastening a saddle, trunk straps, auto straps, wagon straps, et cetera, where a steady tight strain is needed on the strap.

More particularly the present invention consists in the provision of a device of the 20 above mentioned character providing a main frame in which is mounted for swinging and sliding movement, a secondary frame, while coöperating therewith is the improved catch means mounted on the main frame and engageable with the movable frame subsequent 25 to engaging a strap in the latter for locking the movable frame to consequently prevent accidental disengagement of the strap.

Among the other aims and objects of this 30 invention may be recited the provision of a device of the character described, with a view to compactness, and in which the number of parts are few, the construction simple and the cost of production low and 35 the efficiency high.

Other improvements and novel details in the construction and arrangement of the various parts of the apparatus will be brought out more in detail in the description 40 to follow, which for a clear understanding of the invention should be considered in connection with the accompanying drawings forming a part hereof, and wherein is disclosed for the purpose of illustration a convenient and satisfactory embodiment of the 45 invention. It is to be noted in this connection that minor changes in the construction and arrangement of parts may be made without departing from the principle of 50 operation of the various parts.

The invention is clearly illustrated in the accompanying drawings, in which—

Figure 1 is a top plan view of the device.

Fig. 2 is a section taken on line 2—2 of

55 Fig. 1.

Fig. 3 is a central vertical sectional view through the structure of Fig. 1.

Fig. 4 is a section on the line 4—4 of Fig. 1.

Fig. 5 is a perspective view of the secondary frame forming part of the invention.

Similar characters of reference are employed in all of the above described views, to indicate corresponding parts.

Referring now, more particularly, to the accompanying drawings there is illustrated a strap 5 one end of which is attached to the buckle generally designated 6 while the free portion of the strap is removably engaged in the buckle.

In the present instance the improved buckle consists of a main rectangular looped frame 9 connected near its upper portion by means of a relatively wide cross bar 10 which is integral with the opposite sides of the loop and provided with spaced vertical slots 11 for a purpose that will hereinafter appear. The lower end of the main frame is constructed in the form of a rod 12, the ends of which are riveted to the outer ends of the side of the frame as at 13 for a purpose that will hereinafter become apparent. The opposite sides of the frame are also provided with opposed vertical openings 14 at points near the lower ends, also for a purpose that will hereinafter become apparent. A substantially inverted U-shaped secondary metallic frame 15 is now employed and has projecting from opposite points on its sides trunnions 16 which are swingable in the openings 14 preparatory to the fastening of the rod 12 which forms a part of the main frame. The intermediate portion 17 of the secondary frame is also formed with an opening 18 near the upper end of the frame for a purpose that will presently appear, while projecting from the lower edge of the intermediate portion 17 is a finger piece 19. The sides of the secondary frame are formed with opposed vertical slots 18' in which are slidably and rotatably engaged the trunnions of a roller 19' rectangular in cross section, the purpose of which will become apparent.

In order to lock the secondary frame with 105 in the main frame subsequent to the passing of the strap over the lower portion of the secondary frame and beneath the rod 12 at the lower end of the main frame an improved catch indicated in its entirety by 110

the numeral 20 is employed and consists of a plate like body 21 in which is mounted the outer portions of screw bolts 22, the shanks of which operate in the slots, while the lower 5 edge of the plate is formed with a lip or flange 23 which engages the upper portion of the secondary frame near the opening 18 therein subsequent to the sliding of the secondary frame upwardly. A knob 24 is connected to the outer face of the plate like body 20 to facilitate the sliding of the catch on the cross bar 10.

In use, assuming that the parts have been assembled in a manner described and as illustrated in the drawings the free portion of the strap 5 is passed beneath the main frame and engaged over the roller 19' in the secondary frame, while the free portion thereof is finally passed beneath the rod 12 of the main frame so as to lie between this rod and the roller 19' which acts to clamp the strap. The secondary frame is now swung inwardly whereupon the catch is slid downwardly so that the lip or flanged end 23 thereof will 25 engage the upper portion of the frame so as to lock the secondary frame and consequently prevent accidental disengagement of the strap 5 from position.

What is claimed is:

30 1. A buckle of the character described including a main frame, a secondary frame swingably mounted therein, a roller substantially oval in cross section swingably and slidably mounted in the secondary frame and adapted to be engaged by a strap, said roller being subsequently slid to clamp the strap against the main frame, and a catch consisting of a plate like body slidably mounted on the main frame, and a lip on one 35 end of the body for engaging the secondary frame to lock the movable frame against movement.

40 2. A buckle of the character described including a main rectangular frame, a cross

bar connecting the side of the frame near 45 one end thereof and formed with spaced slots, the sides of the frame being provided with opposed openings near the opposite end, a secondary frame, opposed trunnions projecting from the sides thereof and near one 50 end for engagement in the openings in the main frame for swingably supporting the secondary frame, a roller substantially oval in cross section slidably and rotatably mounted in the sides of the secondary frame and adapted to be engaged by a strap, said roller being slid subsequently to clamp said strap against the main frame, a catch consisting of a plate like body formed with a lip, and means anchored in the plate like body and operable in the slots in the cross bar for slidably connecting the plate like body to the cross bar to permit of the sliding of the catch to engage the secondary frame to latch the latter against movement. 55

3. A buckle of the character described embodying a main frame for engagement at one end with a strap, the said frame being formed at the other end with a transversely disposed rod, a secondary frame pivotally 70 mounted within the main frame, a roller substantially oval in cross section and pivotally mounted in the secondary frame adjacent the said rod thereof, the said main frame being formed with a transversely disposed bar adjacent that end connecting with the strap, and a latch carried by the said transversely disposed bar and engageable with the secondary frame to preclude its swinging other than in one direction, whereby that end of the strap opposite the one connected with the main frame may be passed around the said roller and underneath the said rod of the main frame to have this end of the strap secured to the buckle 80 as herein shown and specified.

In testimony whereof I affix my signature.

WILLIAM LOREN DAVIS.
